DESIGN FOR AN ELECTRIC PLUG

Albert E. Grant, New York, N. Y.

Application April 5, 1934, Serial No. 51,313

Term of patent 7 years

To all whom it may concern:

Be it known that I, ALBERT E. GRANT, a citizen of Great Britain, and resident of New York, in the county of New York and State of New York, have invented a new, original, and ornamental Design for Electric Plugs, of which the following is a specification, reference being had to

the accompanying drawing, forming part thereof, in which, Figure 1 is a plan view, Figure 2 is a side elevation, and Figure 3 is an end elevation.

I claim:

The ornamental design for an electric plug, as shown.

ALBERT E. GRANT.
